Primary Examiner — Jasmine Mlinarcik

(57) **CLAIM**

The ornamental design for a ventilated bucket hat, as shown and described.

DESCRIPTION

FIG. 1 is a perspective view of a ventilated bucket hat; FIG. 2 is a front elevation view thereof;

FIG. 3 is a rear elevation view thereof;

FIG. 4 is a right side elevational view thereof;

FIG. 5 is a left side elevational view thereof;

FIG. 6 is a top plan view thereof; and,

FIG. 7 is a bottom plan view.

The broken lines define portions of the ventilated bucket hat that form no part of the claimed design.
